H. P. ANDERSON

LOCOMOTIVE FIRE BOX

Filed May 6, 1921

1,446,081

UNITED STATES PATENT OFFICE.

HOWARD PIERCE ANDERSON, OF ST. LOUIS, MISSOURI.

LOCOMOTIVE FIRE BOX.

Application filed May 6, 1921. Serial No. 467,468.

To all whom it may concern:

Be it known that I, HOWARD P. ANDERSON, a citizen of the United States, residing at St. Louis, Missouri, have invented a certain 5 new and useful Improvement in Locomotive Fire Boxes, of which the following is a full, clear, and exact description, such as will enable others skilled in the art to which it appertains to make and use the same, reference 10 being had to the accompanying drawings, forming part of this specification.

My invention relates to locomotive fire box construction and comprises a new fire pan structure with associated parts, and connections from same to the other portions of 15 the fire box.

The main object of my invention is to provide a rigid one-piece cast fire pan adapted 20 to carry the refractory lining of the fire box and to prevent accidental admission of air to the interior of the fire box, such as usually takes place where refractory lining is carried on open framework or on tubes.

I also desire to eliminate much of the 25 fitting and assembling required on built-up fire pans by providing my cast fire pan with burner, slag, and air openings, with suitable burner, slag pocket and door attaching flanges, and with such other integral ele- 30 ments as will appear hereinafter and as may be required for a complete fire pan installation.

A still further object of my invention is 35 to provide a fire box construction in which a single fire pan casting may be used in different locomotives, even though the size of the fire box varies substantially.

In the drawings—

Figure 1 is a side elevation of the lower 40 portion of the fire box of a locomotive, showing my improved fire pan and fire box attaching construction.

Figure 2 is a vertical longitudinal section through the center of the fire pan.

Figure 3 is a vertical transverse section on line 3—3 of Figure 1.

Figure 4 is an end view of the slag pocket looking in the direction of the arrow A, in Figure 1.

Figure 5 is a modified detail of the burner opening with a burner positioned therein.

A fire box mud ring or foundation ring is indicated at 1, and extending inwardly therefrom I prefer to provide a separate 55 member 2 which serves to support a portion of the refractory lining 3 of the fire box and

also an integral cast steel fire pan 4 which extends substantially throughout the bottom of the fire box and is adapted to carry refractory lining elements. The inner end of 60 member 2 is provided with a depressed rim 5 which engages flange 6 of the fire pan 4 and permits the top of flange 6 to be flush with the top of member 2. A reinforcing rib 7 is provided on member 2 near rim 5. 65

Fire pan 4 is provided with a cored opening 8 near its forward end, which opening is surrounded by vertical flanges 9 and a horizontal flange 10, the latter being adapted to support an oil burner 11 of any commercial type. I provide a shim 12 which cooperates with flange 10 to direct the flame from burner 11 as desired, the burner and shim being held in adjusted position by means of bolt 13. 75

In Figure 5 I have shown a modified construction in which a burner 14 is mounted beneath a supporting flange 15 to which the burner is secured by bolts 16. A shim 17 may be inserted inwardly from bolt 16, as 80 shown, to direct the flame from the burner downwardly, or may be positioned outwardly from bolt 16 to direct the burner and flame upwardly.

Flanges 9 are provided with integral 85 bosses or lugs 18 adapted to be drilled for the insertion of hinge pins 19 for a door 20. The inside faces of flanges 9 and 10 adjacent the edges of door 20 will be chipped smooth to fit the door. 90

A cored opening 21 is provided in the bottom of the fire pan near the rear thereof to afford a slag outlet and a slag pocket casting 22 is bolted to the bottom of pan 4 as indicated. Surrounding opening 21 is a vertical 95 flange 21^a which serves to retain and protect the adjacent edges of the refractory material. The pocket 22 is preferably cast in one piece and is provided with door hinge lugs 23 from which is swung a door 24. The 100 sides of fire pan casting 4 are provided with a series of parallel air inlet openings 25, and it will be understood that the refractory lining is omitted directly in front of these holes. On the outer face of the casting adjacent holes 25 I provide two or more integral lugs 26 adapted to form hinge elements to receive pins 27. A door casting 28 is 105 swung from lugs 26 and serves to close the openings 25. 110

To secure an adjustment in the amount of air admitted to the interior of the fire

- box, I provide an integral projection 29 on the fire pan at one end of the door 28. Projection 29 has a quadrant-shaped portion 30 in which are drilled a series of holes 31 successively spaced at increasing distances from the side of the fire pan. The end of door 28 is provided with a lug 32 and a hole 33 is drilled therein and is adapted to be aligned with any of the holes 31 in projection 29.
- 10 By means of a suitable pin, the door may be secured in closed position, as shown in Figure 3, or may be secured in varying open positions by means of different holes 31.

It will be understood that the above description embodies a preferred construction of my invention, but I do not wish to be understood as being able to use my improved fire pan only in combination with each and every one of the integral elements mentioned. In some installations it may be found desirable to provide separate attaching lugs and projections or to secure the burner and door mountings, etc., in different manners. This may be done without departing from the essential feature of my invention which consists in constructing a fire pan from a substantially one-piece casting. Member 2 is an expedient which may sometimes be found unnecessary and the pan may be so constructed as to be secured directly to the mud ring without the interposition of another member. I contemplate such construction in the commercial development of my invention and any other variations which properly come within the scope of the following claims.

I claim:

1. In a locomotive fire box, a one-piece casting forming a fire pan provided with integral bottom and side walls adapted to extend substantially beneath an opening in the bottom of the fire box proper and upwardly to the edges of said opening and having an opening in one of its side walls 40 for receiving a burner, and an integral flange on said casting adjacent to said opening for supporting the burner.

2. In a locomotive fire box, a one-piece casting forming a fire pan adapted to extend substantially throughout the open bottom of the fire box and to be lined with refractory material, and having an opening for receiving a burner, an integral rigid flange on said casting adjacent to said opening for supporting the burner, and means 55 adjustably positioned on flange for varying the direction of the products of combustion from the burner.

3. In combination, a locomotive fire pan 60 casting, an opening therein, an integral flange adjacent said opening, a movable shim

supported on said flange, a burner projecting through said opening and supported at spaced points on said flange and on said shim, and a bolt holding said burner and 65 shim in predetermined position on said flange.

4. In a locomotive fire box, a one-piece fire pan casting adapted to support the refractory bottom of the fire box, air and fuel inlet 70 openings, flanges surrounding said openings, doors for said openings, and hinge pin bosses formed integral with said flanges for mounting said doors.

5. In a locomotive fire box, a fire pan casting 75 adapted to support the refractory bottom of the fire box, a series of air inlet openings in said casting, integral lugs on the exterior of said casting adjacent said openings, and an elongated door hinged on said lugs 80 and extending over all of said openings.

6. In a locomotive fire box, a fire pan casting adapted to support the refractory bottom of the box, air inlet openings in said casting, integral door hinge elements 85 adjacent said openings, an integral projection adjacent said openings, and a series of holes in said projection extending outwardly from said casting.

7. In a locomotive fire box, a fire pan casting 90 adapted to support the refractory bottom of the fire box, a series of air inlet openings in said casting, integral lugs on the exterior of said casting adjacent said openings, an elongated door hinged on said lugs and 95 extending over all of said openings, an integral quadrant bracket on said casting adjacent the end of said door, a lug on the end of said door parallel with said bracket, a series of holes in said bracket spaced at different distances from said casting, and a hole in said door lug adapted, as said door is opened, to be aligned with any of said bracket holes.

8. In a locomotive fire box casting, a mud 105 ring, a refractory element carrying member extending inwardly therefrom, a depressed rim on the inner end of said member, and a one-piece fire pan casting adapted to carry refractory elements supported upon said depressed rim and having its top face even 110 with the top face of said member.

9. In a locomotive fire box, a mud ring, a cast member extending inwardly therefrom, having an integral depressed rim on 115 the inner end thereof and a reinforcing rib on its lower face adjacent to said rim, and a cast fire pan supported upon said rim.

In testimony whereof I hereunto affix my signature this 27th day of April, 1921.

HOWARD PIERCE ANDERSON.
